AUTOMATIC DIE CASTING MACHINE

Filed July 14, 1921

2 Sheets-Sheet 2

UNITED STATES PATENT OFFICE.

ROBERT E. BYRD, OF ERIE, PENNSYLVANIA.

AUTOMATIC DIE-CASTING MACHINE.

Application filed July 14, 1921. Serial No. 484,788.

To all whom it may concern:

Be it known that I, ROBERT E. BYRD, a citizen of the United States, residing at Erie, in the county of Erie and State of Pennsylvania, have invented new and useful Improvements in Automatic Die-Casting Machines, and I do hereby declare the following to be a full, clear, and exact description of the invention, such as will enable others skilled in the art to which it appertains to make and use the same, reference being had to the accompanying drawings, and to the letters of reference marked thereon, forming part of this specification.

My invention relates to improvements in die-casting machines, and the object thereof is to provide a machine which will close the molding die, force molten metal into the die cavity, open the die, and eject the finished casting from the die, and perform said sequences of operation automatically without the aid of the operator.

Other objects of invention will appear hereinafter in the description of the details of mechanism.

The features of my invention will appear hereinafter and are illustrated in the accompanying drawings in which:

Figure 1, is an end elevation of my improved die casting machine.

Figure 2, is a central section of the melting pot, plunger and casting die in position to receive molten metal.

Figure 3, is a side elevation of the machine shown in Fig. 1 the heating tank being shown in transverse central section.

Figure 4, is a plan view of the same.

Figure 5, is an enlarged plan view die-holding and operating mechanism having a portion thereof broken away.

Figure 6, is a plan view of a fragment of the plate upon which the die-holding mechanism rests.

In these drawings A indicates the base plate of the machine upon which is placed a pedestal A', which has formed on the upper end thereof a tank or melting pot A², the upper end of said pedestal extending upwardly beyond the bottom of said melting pot A². The upper end of said pedestal is provided with a longitudinal opening a which communicates with the tank A² through the openings a' (see Figs. 2 and 3).

Within the longitudinal opening a in the upper end of the pedestal A' is placed a piston B having a central longitudinal pas-

sage b therethrough. This piston is operated by means of a lever C (see Fig. 3) which is fulcrumed upon a link C' which is pivoted upon a bracket C² on the melting pot A², said lever being pivoted to the upper end of the piston B by means of pins c.

Upon the base plate A I place upright frames D, D' in the upper end of which is mounted a shaft D²; and upon the shaft D², directly under the lever C, I place a cam wheel E, and upon the lever C there is secured a bracket E', which carries a roller e, which engages the cam wheel E, so that as the cam wheel E rotates, the lever C is operated thereby to cause the piston B to reciprocate in the opening or chamber a in the upper end of the pedestal. Said piston moves downward by gravity, and is raised by the upward cam driven movement of the lever C.

Upon the upper end of the piston B I secure an upright bracket B' having an arm b' which overhangs the upper end of the piston B. Upon the upper end of the piston B is secured a plate F having a hole f therethrough which registers with the passage b in the piston B. Upon the plate F there is pivoted by means of a pivot F' the die-holding mechanism of my machine, consisting of a swinging die-bar G, (see Fig. 5), provided with an operating handle g, and another die-bar G' which has one end thereof pivoted to an ear g' by means of a pin g².

The bar G' is provided with a hook arm g³ which is adapted to engage the upright bracket B' and thereby limit the lateral movement of the die-bar G' as hereinafter described. The die-bars G and G' are provided with recesses H, H' with which passage ways h, cored out in the die-bars G and G' communicate. The die-bar G is provided with slide-ways G² in which are placed core-pin slides J, J'. Secured upon the plate F are cam plates F² which engage a roller (not shown) secured on the under side of the core-pin slide J by means of a bolt j; and on the opposite end of the plate F are secured a pair of spaced bars F³, F⁴, between which a roller j', secured on the under side of the core-pin slide J' by means of the pin j² operates.

Pivoted on the die-bar G is a latch hook K having a slotted opening into which the pin j² on the core-pin slide J' projects; the free end of said latch hook being adapted to engage a stud-pin g⁴ on the die-bar G' when

the dies are closed as shown by full lines in Fig. 5.

The bar F^4 (see Fig. 6) is provided with an adjusting screw f' which is adapted to be engaged by the roller j' for the purpose of forcing the core-pin slide J' firmly against the die hereinafter described, and the bar F^3 is cut away opposite said adjusting screw to give clearance for said roller.

10 The bar F^2 is preferably provided with a cam-like projection f^2 to be engaged by the roller j' to cause the latch hook K to become disengaged from the stud-pin g^4 before the hook arm g^3 engages the upright bracket B' .

15 Secured against the adjacent faces of the die-bars G and G' are the casting dies L , L' , said dies being secured on said die-bars G and G' so that they cover the recesses H and H' by means of screws l . The dies L 20 and L' are of ordinary construction as regards the casting cavity or mould, the same being formed according to the image desired.

The core-pin slides may be provided with 25 core-pins j^3 which extend into the mould cavity through openings formed equally in each half of the complete die; and likewise the two halves of the die L , L' are provided with an opening l' which coincides 30 with the hole f in the plate F when the die is closed, as shown in full lines in Fig. 5.

In order to eject the casting from the die L when the die is opened, I provide a 35 spring-pressed plate M which is slidably mounted on stud bolts M' secured in the die arm, and a spring M^2 is placed between the die arm G and the plate M to yieldingly maintain the plate in the position thereof shown by full lines in Fig. 5. From 40 the plate M ejector rods m pass through openings in the die-bar G and die L , the inner ends thereof being flush with the wall of the die-cavity.

Secured to the plate F is a stationary 45 arm M^3 which is provided with a post M^4 against which the plate M strikes when the die-arm G is moved to the position shown in broken lines in Fig. 5, which depresses said plate and forces the ejector rods m 50 inwardly, which ejects the casting from the die L , said casting having been carried out of the die L' by the core-pins j^3 before they have been withdrawn, as hereinafter described.

55 The plate F is cut away as shown in Fig. 6, a sufficient amount to permit the casting to drop out from between the dies when it has been ejected from the die. Suitable water connections are made with the cored passages h to provide for a circulation of cold water through the recesses H and H' for the purpose of keeping the dies L and L' cool in order that the molten metal will be instantly chilled when it contacts therewith.

Secured in the overhanging arm b' of the bracket B' (see Fig. 2) is a swinging arm N with which a spring n is connected, the opposite end thereof being connected to a post n' in the bracket B' . Secured in the die arm G is a post P in which is placed a screw P' which is adapted to engage the swinging arm N and thereby force it backward as the die arm G is closed, thereby causing said swinging arm N to engage the dies L , L' and force them firmly down upon the plate F during the casting process.

In order to provide mechanism to automatically open and close the die-mechanism hereinbefore described, I provide a lever Q , 80 which is fulcrumed upon a shaft Q' , mounted in suitable bearings q on the base plate of the machine, said lever Q extending upwardly to a point adjacent to the handle g of the die bar G .

The lever Q is provided at its upper end with upwardly extending bars q^1 , q^2 which are adapted to engage the handle g of the die-bar G at opposite sides thereof. The bar q^1 is provided with a screw q^3 to engage said handle so that the amount of lost motion between the lever Q and handle g can be regulated.

The lever Q is provided with a safety arm R , which, when the lever Q is swung toward the left, prevents the lever C from dropping, by means of any accident, when the dies are open. The safety arm R is provided with a spring pressed cushion bolt r adapted to receive the lever C when it 100 is dropped by the cam wheel E . This bolt r can be adjusted by means of the nut r' to regulate the amount of metal forced into the dies.

To operate the lever Q I provide a drum 105 S on the shaft D^2 , upon which is secured a cam-bar S' having suitable shape to adapt it to engage the roller Q^2 secured on the lever Q and swing it toward the left a sufficient distance to swing the die-bar G to the position thereof shown by broken lines in Fig. 5. A spring Q^4 is provided to return the lever Q and die-arm G to the positions thereof shown by full lines in Figs. 3 and 5, said spring causing the roller Q^2 110 to continue in engagement with the cam S' during the movement of the lever Q to the left and the return movement thereof to the right.

The mechanism which I preferably use to rotate the shaft D^2 consists of a shaft T journalled in suitable bearings t on the upright frame D' . Upon the shaft T is secured a worm T' which intermeshes with a worm-gear T^2 . Upon the shaft T is placed a band pulley U , and I provide on the shaft T a clutch U' by means of which the mechanism can be stopped when desired.

To provide heat for the melting pot A^2 , I place fluid fuel burners V of ordinary con-

struction thereunder, and to conserve the heat I place a sheet iron curtain W around said pot, said curtain being provided with openings w adjacent to the upper edge 5 thereof to provide for the escape of the products of combustion.

In operation, metal to be melted is placed in the pot A², and when the same has been melted and flows through openings a' into 10 the chamber a, power is then applied to the shaft T which causes the shaft D² to revolve the cam-wheel E which permits the lever C to drop down upon the cushion bolt r. The plunger or piston B with the die operating mechanism thereon is lowered by the 15 lever C which forces some of the molten metal trapped by the piston in the chamber a, upward through the passage b into the dies L, L', where it comes into contact with 20 the cold walls of the dies, and a thin film of metal is immediately chilled and hardened, and the continued revolution of the cam-wheel E raises the lever C, and piston B, which withdraws that portion of the 25 molten metal from the central portion of the casting which has not become hardened, back down in the piston B.

The drum S and cam-bar S' upon the shaft D² has by this time revolved far 30 enough so that the cam-bar S' engages the roller Q² on the lever Q which causes the same to swing toward the left thereby swinging the die-bars G and G' to the position thereof shown by broken lines in Fig. 35 5, which movement shears off any metal projecting downward in the hole l' in the dies.

The core-pins j³ which are carried on the slides J and J' during the initial movement 40 of the die-bar G extend into the casting and force it out of the die L' when the hook g³ engages the bracket B' and arrests the side-wise movement of the die-bar G'; meanwhile the continued movement of the 45 die-bar G, the latch-hook K having been previously disengaged from the stud g⁴, as hereinbefore described, carries the ejector plate M into contact with the post M⁴, which ejects the casting from the die L, the die- 50 pins j³ having by this time been withdrawn from the casting as hereinbefore described, and the casting drops downward into a receptacle (not shown) placed to receive the same.

55 The continued revolution of the drum S and its cam-bar S' now allows the spring Q⁴ to swing the lever Q toward the right, which closes the die-bars G and G' back to the position thereof shown by full lines in 60 Fig. 5, when the cam wheel E is in the position shown in Fig. 3, ready to repeat the operation.

It will be observed from the description 65 of the construction and operation of the machine, that I have made provision for

firmly holding the dies down upon the plate F, and the core-pin slides firmly against the sides of the dies during the casting process, thus eliminating the escape of metal from the dies during casting, so that the castings 70 come out of the dies free from fins and projections of waste metal.

Having thus fully shown and described my invention so that others can utilize the same, I do not desire to limit myself to the exact form and arrangement of mechanism shown and described, as many alterations 75 can be made therein by those skilled in the art without departing from the scope of my invention; therefore what I claim as new and desire to secure by Letters Patent is:—

1. In a machine of the class described, a melting pot, a cylinder within said pot, a vertically movable piston within said cylinder having a longitudinal passage therethrough, a mould die composed of a plurality of parts supported upon and movable with said piston, mechanism mounted upon said piston adapted to hold said mould parts 80 together during the casting process and to separate them to drop the casting out, and mechanism to operate said piston and die holding mechanism.

2. In a machine of the class described, 95 a moulding die composed of two parts, a plate on which said die rests, a die arm to carry one part of said die pivoted to said plate to swing horizontally thereon, another die arm to carry the other part of said die articulated on the first named die-bar and adapted to swing laterally with relation thereto, means to lock said bars together during the casting operation, means to unlock the same when said first named die-bar is operated to open said die, cylinder and piston mechanism to force molten metal into said die and lever and mechanisms to operate said piston and die-bar mechanisms in timed sequence with relation to each 100 other.

3. In a machine of the class described, cylinder and piston mechanism, a plate secured on said piston, a die-bar pivoted on said plate, another die-bar articulated on the first named die-bar, one-half of a moulding die secured on the adjacent faces of said die-bars so that they will match together when said die-bars are closed, means to lock the free ends of said die-bars together 115 during the casting operation, means to automatically unlock said die-bars when said bars are operated to open said dies, means to press said die down upon said plate when the die is closed, means to supply molten metal to said cylinder, lever and cam mechanism to operate said piston to force molten metal into said die, and lever and cam mechanism to operate said die-bars to open and close said die. 120 125 130

4. In a machine of the class described, a moulding die holder comprising substantially a base plate, a die bar pivoted thereon, core-pin slides mounted in said die-bar adapted to engage opposite sides of said die, means secured on said base-plate to cause said core-pin slides to move longitudinally with relation to said die-bar when said die is opened, another die-bar hinged 10 on the first mentioned die-bar, a moulding die part secured thereon to register with the first mentioned die part when the die parts are closed together, a latch hook pivoted on the first mentioned die-bar and adapted to engage a stud on the second mentioned die-bar, means on one of said core-pin slides adapted to unhook said latch from said stud during the opening movement of said die-bars, and means to arrest the movement 15 of the second mentioned die-bar when said latch hook has been unhooked.
5. In a machine of the class described, a die-holding mechanism comprising articulated die-bars pivoted on a base-plate, a spring actuated plate slidably mounted upon and in front of one of said die-bars, ejector rods secured on said plate and slidably projecting through said bar and die thereon, and means to depress said plate 20 when said die-bars are swung to their open position.
6. In a machine of the class described, a plate, articulated die-bars pivotally mounted on said plate, moulding dies secured on said bars, said die-bars being adapted to move said dies laterally before opening the same, piston mechanism to supply moulten metal to said dies, a lever to operate said piston, another lever adapted to operate said die-bars, and mechanisms adapted to operate said levers in timed sequence with relation to each other.
7. In a machine of the class described, a cylinder, means to supply moulten metal to said cylinder, a piston in said cylinder 45 having a longitudinal opening therethrough, a plate secured on the upper end of said piston having a hole therethrough which registers with the opening in said piston, die-holding and operating mechanism mounted on said plate, moulding dies secured in said die-holding mechanism so as to communicate with the hole in said plate, means to press said die against said plate when the same is closed, a lever to operate said piston, another lever to operate said die-holding mechanism, a bar secured on the last named lever to prevent the first named lever from moving downward when the moulding dies are open, 50 and cam mechanisms adapted to operate said levers in timed sequence with relation to each other.
8. In a machine of the class described, a cylinder, means to supply moulten metal 65 thereto, a vertically movable piston in said cylinder having a longitudinal passage therethrough, die operating mechanism supported on the upper end of said piston, dies secured therein and communicating with 70 said passage, a lever adapted to lower and raise said piston, another lever adapted to operate said die-holding mechanism to open said die, a spring-pressed bolt supported on said second named lever adapted to limit 75 the downward movement of the piston lever, and cam mechanisms adapted to operate the piston lever and die-holding mechanism lever in timed sequence with relation to each other.

In testimony whereof I affix my signature.

ROBERT E. BYRD.
